(Cl. D58—11)

To all whom it may concern:

Be it known that I, Jacob H. Millstein, a citizen of the United States, residing at Jeannette, in the county of Westmoreland and State of Pennsylvania, have invented a new, original, and ornamental Design for a Toy Glass Airplane for Candy Pellets, of which the following is a specification, reference being had to the accompanying drawing, forming part thereof.

In the drawing:

Figure 1 is a top plan view of a toy glass air-

plane for candy pellets, showing my new design,

Figure 2 is a bottom plan view,

Figure 3 is a side elevational view,

Figure 4 is a front end elevational view, and Figure 5 is a rear end elevational view.

I claim:

The ornamental design for a toy glass airplane for candy pellets, as shown.

J. H. MILLSTEIN.
